UNITED STATES PATENT OFFICE.

GEORGE A. THORNTON, OF SCHENECTADY, NEW YORK, ASSIGNOR TO
GENERAL ELECTRIC COMPANY, A CORPORATION OF NEW YORK.

BRUSH.

No. 852,686.

Specification of Letters Patent.

Patented May 7, 1907.

Application filed September 11, 1906. Serial No. 334,184.

To all whom it may concern:

Be it known that I, GEORGE A. THORNTON, a citizen of the United States, residing at Schenectady, county of Schenectady, State of New York, have invented certain new and useful Improvements in Brushes, of which the following is a specification.

My invention relates to brushes for dynamo-electric machines and has for its object to improve the same.

It is sometimes desirable to provide a carbon brush with a metal plate adapted to be engaged by the follower so as to protect the end of the brush; but difficulty has heretofore been experienced in securing such a plate effectively in place in a simple and cheap manner.

In one of its aspects my invention may be considered as relating to a novel form of protective device and means for securing it to the brush, whereby a reliable electrical and mechanical union between the parts is readily obtained.

My improved protective device may be used to advantage to secure a pig-tail to the brush and therefore, in a further aspect of my invention, it may be considered as consisting of a novel means for and method of connecting a pig-tail to a brush.

For a full understanding of my invention and of its objects and advantages, reference is to be had to the following detailed description taken in connection with the accompanying drawing. The scope of my invention, is, however, defined in the appended claims.

In the drawing, Figure 1 shows in perspective a brush and a protective plate ready to be placed upon the brush and secured thereto; Fig. 2 is a view similar to Fig. 1, showing in addition a pig-tail and the manner in which the protective plate co-acts with the pig-tail to secure it in place; Fig. 3 shows the several members illustrated in Fig. 2 united into one complete whole; and Fig. 4 is a further modification.

Reference being had to Figs. 1—3 of the drawing, 1 indicates a carbon brush of any suitable type, and 2 is a strip of gauze or a perforated plate, consisting preferably of copper and having preferably the same shape as the top of the brush. 3 is a pig-tail made up of a number of fine strands which are preferably spread out at one end, as at 4, so as to cover the top of the brush, or at least

the major portion thereof. The member 2 is laid upon the top of the brush in the construction shown in Fig. 1 or upon the top of the portion 4 of the pig-tail in the construction shown in Fig. 2, and is temporarily secured in position on the brush in any suitable manner, as, for example, by clamping or by means of a thread or other suitable binding member. The end of the brush upon which the plate is mounted is then immersed in an electro-plating solution, the brush forming one electrode as is usual in electro-plating. The deposited metal, which is preferably copper, enters between the meshes of the gauze strip or into the perforations of the plate, if a perforated plate is used, and into intimate engagement with the brush, or the strands of the pig-tail and the brush, as the case may be. Also, a band 5 of the deposited metal will be formed about the end of the brush, joining the edges of the member 2 intimately to the brush. I have found that there is thus formed a complete electrical and mechanical connection between the several parts and, where pig-tails are attached in this way, a secure and reliable connection is obtained. In neither case is it necessary to first copper plate the brush as is necessary where protective plates or pig-tails are soldered in place; but the entire process, after the mechanical assembly, includes but the single step of electro-plating.

In Figs. 2 and 3 the pig-tail is shown as projecting from the edge of the brush, but it may be led to the brush from the side, as shown in Fig. 4, the end of the pig-tail in this case being spread as indicated at 4^a.

What I claim as new and desire to secure by Letters Patent of the United States, is,—

1. A carbon brush having a metal strip provided with a plurality of perforations electroplated to one end thereof.

2. A carbon brush having a gauze metal strip electroplated to one end thereof.

3. A carbon brush having a metal strip provided with perforations secured thereto by electrolytically-deposited metal extending into said perforations.

4. In combination, a carbon brush, a gauze strip over one end of the brush, a pig-tail having one end arranged between the brush and the gauze strip, and means for securing the parts together consisting of electrolytically deposited metal entering be-

tween the meshes of the strip and in contact with the end of the brush.

5. The method of securing a pig-tail to a brush which consists in placing the end of the pig-tail between the brush and a gauze strip and securing the whole together by electro-plating.

In witness whereof, I have hereunto set my hand this 10th day of August, 1906.

GEORGE A. THORNTON.
